MEASURING TAPE

Filed Aug. 19, 1926

FIG. 3.

INVENTOR

ADOLPH LANGSNER

By Cheever & Cox ATTYS

UNITED STATES PATENT OFFICE

ADOLPH LANGSNER, OF CHICAGO, ILLINOIS, ASSIGNOR TO EUGENE DIETZGEN CO., OF CHICAGO, ILLINOIS, A CORPORATION OF DELAWARE

MEASURING TAPE

Application filed August 19, 1926. Serial No. 130,219.

This invention relates generally to measuring tapes and particularly to the cases thereof, and has for its object the simplifying of the construction and the cheapening of 5 the cost of manufacture thereof.

It is also contemplated to provide a simplified measuring tape case that may be quickly and easily assembled and yet have all of the strength and durability of the more 10 complicated prior constructions.

Among its other objects the present invention has in view the provision of an outer or finishing cover for the measuring tape case that may be quickly placed on the case and 15 there be held without the use of stitching or similar fastening means or without unprotected edges to become loosened.

The present invention, furthermore, has in view the additional attachment of the outer 20 or finishing cover to the case by the use of the mounting element of the drum upon which is wound the tape line.

With the above and other objects in view, as will be apparent, this invention consists in 25 the construction, combination and arrangement of parts, all as hereinafter more fully described, claimed and illustrated in the accompanying drawing, wherein—

Figure 1 is a side elevation, with parts 30 broken away, of a measuring tape case constructed in accordance with the present invention.

Figure 2 is a vertical section taken along line 2—2 through Figure 1; and

Figure 3 is a similar fragmentary section, enlarged to illustrate the joint between the parts of the measuring tape case and the securing of the outer cover thereon.

Heretofore it has been customary to telescope 40 the two parts of a measuring tape case over the drum and other parts of the device and hold these parts in such positions by means of additional or other elements. The present invention contemplates providing the 45 overlapping or telescope portions of the case with beads, which when the parts of the case are telescoped snap into self-holding interlocking engagement. Thus the case is assembled and held by a means forming a part of 50 the case itself and the necessity of other ele-

ments functioning for this purpose is done away with.

Where the case has been provided with an outer cover of leather or other material it has been the practice to form such outer cover 55 in two sections and to stitch the adjoining edges of these sections one to the other. This has been unsatisfactory because of its expense as a manufacturing operation and the fact that it does not present a finished or attractive appearance. This invention, while utilizing a cover made in two sections, does not require the stitching thereof. It provides a cover which is placed on the case as a part of the assembling thereof, but which is so 60 held in place that there are no exposed edges to become loosened, and a pleasing and finished appearance is presented. This is accomplished by means of a finishing strip secured over the adjoining edges of the cover 65 and held at its ends by the eyelet or frame carrying the roller over which the tape line passes when removed from the case.

Reference being had more particularly to the drawing, 10 designates the two telescoping parts of a measuring tape case. The portions of these parts 10 that are designed to telescope are provided at or adjoining their edges with inward beads or grooves 11. When the parts 10 of the case are telescoped 70 these beads 11 snap into interlocking self-holding engagement and retain the casing assembled.

This construction produces a groove in the rim of the case which is utilized for 75 holding the cover 12 on the casing. As shown in the enlarged view Fig. 3 the adjoining edges 12' of the cover 12 are curved and seated in the groove formed by the outer bead 11. In order to retain the edges 80 12' of the cover 12 in this groove and in order to hide these edges 12' of the covers; a finishing strip 13 is glued or cemented to the cover 12 over the edges 12' thereof.

The outer surface of the strip 13 is convexed while the inner surface is generally flat except in the center where it is provided with a ridge 14. This ridge 14 projects toward the groove created by the outer bead 11 and overlies the edges 12' of the cover 12. 100

This ridge 14 of the finishing strip is provided as an expedient for properly centering the strip in position about the periphery of the case and exactly over the juxtaposed edges 12' of the two separate cover pieces. This finishing strip 13 is in no sense a clamping strip but serves merely to hide the rough edges of the covers. The glue or cement is wholly relied upon to adhere the covers 12 and the edges 12' thereof in position and also to secure the flexible finishing strip 13 thereto when the same is made of material such as leather or the like which may be suitably adhered to the cover pieces.

An eyelet or frame 15 embraces the telescoped portions of the parts 10 of the case at the opening through which the tape line 16 is removed from the case. The flanges of this eyelet 15 engage the terminals of the finishing strip 13 and not only hold them in place but protect and conceal them.

At its center the sides of the cover 12 are apertured for the mounting of the drum 17 upon which the tape line 16 is wound. This drum 17 is inserted for rotation in one side 10 of the case and is provided with a lateral lip 18 which bears upon the edges of the cover 12 surrounding the opening in the side 10. Thus the lip 18 of the drum 17 centrally secures one side of the cover 12 in place on the case.

A hub 19 forms the axle of the drum 17 and extends from one side 10 to the other side 10 of the case. Adjoining the outer face of the drum 17 the hub 19 is grooved for cooperation with the drum while the opposite end has a friction fit with the flanged bushing 20 inserted through the side of the case and cover 12. The flange 21 of this bushing 20 is located on the exterior of the case and cover 12 and bears firmly against the edges of said cover around the opening in the case through which the flanged bushing 20 passes. In this manner the other side of the cover 12 is securely held in place on the case.

From the foregoing it will be clear that the present casing may be assembled and covered in what may be termed a single operation. No unprotected edges are present in the cover nor is there any unsightly stitching showing. Not only is the appearance of these devices improved by the present invention but the cost of manufacture is reduced without sacrificing any of its durability or strength.

Having thus described my invention, what I claim as new and desire to secure by Letters Patent is:

1. A measuring tape having a two part case with a bead on each part, said beads snapping into interlocking engagement upon the telescoping of said parts.

2. A measuring tape having a case of two

telescoping parts, and a bead on each part, said beads being adapted to snap into interlocking self-holding engagement when the parts are telescoped.

3. A measuring tape having a case of two telescoped parts, each part being provided with an inward bead, said beads adapted to snap into interlocking self-holding engagement as said parts are telescoped.

4. A measuring tape having a case of two telescoped parts, each part being provided with an inward bead, said beads adapted to snap into interlocking self-holding engagement as said parts are telescoped, and a two part cover for said case, the adjoining edges of which are seated in said beads.

5. A measuring tape having a case of two telescoped parts, each part being provided with an inward bead, said beads adapted to snap into interlocking self-holding engagement as said parts are telescoped, a two part cover for said case having its adjoining edges seated in the outer of said beads, and a finishing strip over the adjoining edges of said cover.

6. A measuring tape casing formed with a groove in the periphery thereof, a cover for said case with its edges arranged in said groove, and a finishing strip arranged over and concealing the edges of the cover and securing them in the groove.

7. In a tape reel, a two part casing, a cylindrical flange on each part, said flanges forming a groove in the peripheral wall of the casing and being provided with means to snap into interlocking self-holding engagement, cover pieces for said casing having their marginal edges arranged in said groove and a finishing strip overlying said edges.

8. In a tape reel, a two part casing, said casing parts having telescoping flanges provided with means to snap into interlocking self-holding engagement, cover pieces having their marginal portions overlying the peripheral wall of said casing and a finishing strip overlying the adjoining edges thereof.

9. In a tape reel, a multi-part casing having portions provided with overlapping means adapted to snap into interlocking engagement, said portions forming a peripheral groove, cover pieces having their marginal edges arranged in said groove and a finishing strip overlying said marginal edges and hiding the same.

10. A measuring tape casing provided with a peripheral groove, a plurality of cover pieces forming a facing for the casing, said pieces having their edges lying in said groove and a finishing band overlying said edges to hide the same, said finishing strip having an internal bead whereby the edges of the cover are pressed into the groove.

11. A measuring tape casing provided with a peripheral groove, cover pieces for the casing having their edges arranged in said

groove inwardly of the peripheral surface of the casing, and a finishing band overlying said edges.

12. In a tape reel, a two part casing, a cylindrical flange on each part, means on said flanges to fasten the parts together and to provide a groove in the periphery of the casing, cover pieces for said parts having their marginal edges arranged in said groove and a finishing strip overlying said edges.

13. In a tape reel, a two part casing, a cylindrical flange on each part, means associated with said flanges to fasten the parts together, said casing being formed to provide a peripheral groove when assembled, cover pieces for said casing having their marginal portions arranged in said groove and a finishing strip overlying said edges.

In witness whereof, I have hereunto subscribed my name.

ADOLPH LANGSNER.
